US0D1052744S

(12) **United States Design Patent** (10) Patent No.: **US D1,052,744 S**
(45) Date of Patent: ** Nov. 26, 2024

(54) **PHOTOTHERAPY DEVICE**

(71) Applicant: **Basolite Ltd**, Spennymoor (GB)
(72) Inventor: **Gordon Dougal**, Spennymoor (GB)
(73) Assignee: **Basolite Ltd**, Spennymoor (GB)
(**) Term: **15 Years**

(21) Appl. No.: **35/516,434**(22) Filed: **Dec. 8, 2022**(80) **Hague Agreement Data**

Int. Filing Date: **Dec. 8, 2022**
Int. Reg. No.: **DM/226620**
Int. Reg. Date: **Dec. 8, 2022**
Int. Reg. Pub. Date: **Feb. 24, 2023**

(30) **Foreign Application Priority Data**

Jun. 10, 2022 (GB) 6213179
Jun. 10, 2022 (GB) 6213180
Jun. 10, 2022 (GB) 6213181

CLAIM

The ornamental design for a phototherapy device as shown and described.

DESCRIPTION

- 1.1 : Perspective view from above
- 1.2 : Perspective view from below
- 1.3 : First side view
- 1.4 : Second side view
- 1.5 : Third side view
- 1.6 : Top
- 1.7 : Bottom
- 1.8 : Fourth side view

(Continued)

In the reproductions, the broken lines depict portions of the phototherapy device that form no part of the claimed design.

1 Claim, 8 Drawing Sheets
